LORING COES, OF WORCESTER, MASSACHUSETTS.

Letters Patent No. 91,605, dated June 22, 1869.

IMPROVED WRENCH-BAR-HEADING MACHINE.

The Schedule referred to in these Letters Patent and making part of the same.

Know all men by these presents:

That I, LORING COES, of the city and county of Worcester, and Commonwealth of Massachusetts, have invented certain new and useful Improvements in Wrench-Bar-Heading Machines, of which the following is a full, clear, and exact description, reference being had to the accompanying drawings, forming a part of this specification, in which—

Figure 1 represents a plan or top view of so much of a Coes wrench-bar-heading machine as is necessary to illustrate my present improvements, and

Figure 2 represents a section on line A B, fig. 1.

To enable those skilled in the art to which my invention belongs, to make and use the same, I will describe it more in detail.

The nature of my invention consists—

First, in the combination, with the stationary bed which supports the sliding anvil-block, in the wrench-bar-heading machine, patented by myself and A. G. Coes, on the 31st day of July, A. D. 1860, of an auxiliary removable bed, made in two pieces, as hereafter explained.

Second, in the combination, with the removable anvil-bed, of certain adjusting-devices, as and for the purpose hereafter explained.

Third, in the combination, with the removable and adjustable anvil-bed, of clearing-holes, as and for the purposes hereafter set forth.

In the drawings—

A is the base, upon which a circular or other proper-shaped bed, B, is placed. In this case the base A has a flange, a, within which the bottom of the bed B fits.

The under side or bottom of the bed B is cored out, as shown at C, and is also provided with two openings, b, one on each side.

A recess or opening is cut through the bed B, for the reception of the upper part of the auxiliary anvil-bed D, which is composed of two pieces, D' D'.

The upper faces of the pieces D' D' are flush with the top of the bed B, while they stand or rest upon the base A, as fully indicated in fig. 2 of the drawings.

The inner upper faces or sides of the pieces D' D' are cut out to receive the anvil-block E, which is to be used and operated in the manner shown and described in the patent before referred to.

The ends of the pieces D' D' are notched or cut out upon their upper inner sides, for the reception of the adjusting-wedges F F, while the bed B is cut out to receive the outer adjusting-wedges G G.

In this instance, wedges G G are shown only on one side, but they may be used on both sides, if preferred, in lieu of a plate or plates d, being used on one or both sides.

It will be seen that in case the anvil-block E wears loose, the pieces D' D' can be set up toward each other, so as to make a good fit again, and that, too,

with but little trouble, all that is required, being to withdraw the inner wedges F slightly, and then drive down the wedges G G, or insert strips d between the backs of the pieces D' D' and the bed B, as indicated at d, in the drawings.

By the use of the wedges F, the pieces D' can be set up close to the anvil-block E, without danger of binding.

If preferred, in any case, strips d and wedges G may be used on both sides at the same time.

It will be understood that the shank of the wrench-bar is to be inserted in the opening e of the anvil-block E, and the slide-dies H H operated from eccentrics or cranks on the upright shafts I I, (only the lower ends of which are shown in the drawings,) the same as in the machine patented by A. G. Coes and myself, and to which reference has been made.

In the patented machine last referred to, the anvil-block E works on ways formed in the bed B, so that when the said ways are worn badly, there is no alternative but to replace the entire bed B, by a new one, thus involving a great expense.

Then, again, the jarring occasioned by the falling or action of the upper hammer or die, (not shown in the drawings,) when the anvil-block rests upon ways formed in the elevated bed-piece B, creates much more injury to the working-parts of the machine than what it does when the anvil-block rests and moves upon ways formed in independent and separate pieces supported upon the base-piece A, as shown in the drawings.

If the anvil-ways in the pieces D' D' become worn, so that the anvil works too low, narrow strips of metal can be placed under said piece, and thus elevate the anvil-block to the proper height again.

During the operation of heading the wrench-bar, scales are thrown off and fall down upon the ways f f.

The scales thus thrown off, are very hard, and are liable to work under the anvil-block, and thus greatly increase the wear of the ways f f, as well as the under side of the anvil-block.

To guard as much as possible against such injurious results in the operation of the machine, I make a hole, g, shown in dotted lines, at each end of each piece D', the hole g leading from the ways f down into the open space under the bed B. By this arrangement the anvil-block, as it moves back and forth, has a tendency to clear the ways f, by forcing the scales over and into said holes, and through which they pass or fall down under the bed B.

There is an opening, J, under the centre of the anvil, the same as in the original Coes heading-machine, but in practice, that has been found insufficient to prevent the difficulty, which is obviated by clearing-holes g.

It will be seen from the foregoing description, that by my present improvements, the value of the original Coes wrench-bar-heading machine is greatly en-

hanced, since the machine will last much longer, while, at the same time, the adjustment of the devices which retain the anvil-block in place can be so readily and accurately made, that there is no danger of the machine making imperfect heads, as is the case in the original machine.

Having described my improved wrench-bar-heading machine,

What I claim therein as new and of my invention, and desire to secure by Letters Patent, is—

1. The combination, with the stationary bed B and base A, of the auxiliary removable bed D, substantially as and for the purposes set forth.

2. The combination, with the parts D' D' constituting the auxiliary bed D, of adjusting-wedges F and G, substantially as and for the purposes set forth.

3. The combination, with the parts D' D', constituting the auxiliary bed D, and wedges F, of thin strips *d*, substantially as and for the purposes set forth.

4. The combination, with the bed which supports the anvil-block, of a clearing-hole or holes, *g*, substantially as described.

LORING COES.
